UNITED STATES PATENT OFFICE.

BRYAN HERBERT SMITH, OF NEW YORK, N. Y., ASSIGNOR TO CLARENCE WHITMAN & CO., INC., OF NEW YORK, N. Y., A CORPORATION OF NEW YORK.

DESIGN FOR COTTON PONGEE SHIRTING.

46,375.

Specification for Design.

Patented Sept. 8, 1914.

Application filed July 3, 1914. Serial No. 848,954. Term of patent 3½ years.

To all whom it may concern:

Be it known that I, BRYAN HERBERT SMITH, a citizen of the United States, and a resident of the borough of Brooklyn, county of Kings, New York city, New York, have invented a new, original, and ornamental Design for Cotton Pongee Shirtings, of which the following is a specification.

Reference is to be had to the accompanying drawing, which illustrates a sample of the fabric, showing the new design.

In the drawing *a* is a colored satin stripe; *b* is plain weave; *c* a satin stripe; *d* plain weave; *e* a colored satin stripe; *f* plain weave; *g* a satin stripe; *h* plain weave; *i* colored

satin stripe; *j* is a section of plain weave, the center of which is a panel formed by the large number of flat V's woven in the fabric in a horizontal direction, the horizontal lines of the V's being very close to each other. Unless otherwise specified, the fabric, sections, cords, etc., are light colored or white.

I claim:

The ornamental design for cotton pongee shirtings, as shown and described.

BRYAN HERBERT SMITH.
